UNITED STATES PATENT OFFICE.

ALBERT J. GURNEY, OF CANTON, OHIO, ASSIGNOR TO THE AMERICAN MINE DOOR CO.,
CANTON, OHIO, A CORPORATION OF OHIO.

TROLLEY AND SIGNAL WIRE HANGER.

Application filed November 7, 1923. Serial No. 673,330.

To all whom it may concern:

Be it known that I, ALBERT J. GURNEY, citizen of the United States, residing at Canton, in the county of Stark and State 5 of Ohio, have invented certain new and useful Improvements in Trolley and Signal Wire Hangers, of which the following is a specification.

This invention relates to an improved 10 trolley and signal wire hanger which while well adapted for general use is more particularly designed to be employed in mines in conjunction with my improved signaling system for mines set forth in a separate 15 application filed November 7, 1923, Ser. No. 673,329.

The invention seeks, among other objects, to provide a hanger not only adapted to sustain a trolley wire but also adapted to 20 sustain a conductor wire directly over the trolley wire in close proximity thereto.

The invention seeks, as a further object, to provide a hanger particularly suited for 25 supporting the conductor wire at its ends, and wherein means will be provided for stretching the wire taut.

And the invention seeks, as a still further object, to provide a hanger embodying a 30 wire holding device which may be shifted from one end of the hanger to the other to suit the direction in which it is desired to arrange the conductor wire.

Other and incidental objects will appear hereinafter.

35 In the drawings:

Figure 1 is a side elevation of my improved hanger,

Figure 2 is a top plan view of the device,

Figure 3 is a vertical sectional view on 40 the line 3—3 of Figure 1, looking in the direction of the arrows,

Figure 4 is a vertical sectional view on the line 4—4 of Figure 1, looking in the direction of the arrows, and

45 Figure 5 is a horizontal sectional view on the line 5—5 of Figure 1, looking in the direction of the arrows.

In carrying the invention into effect, I employ a channel-shaped oblong body plate 50 10, the side flanges of which terminate in ears 11, and formed on the ends of the plate are medial opposite directed brackets 12

provided at their free ends with slots 13. In use, the body plate 10 may be rested against the roof of a mine or other appropriate supporting means such, for instance, as a cross beam 13' in the mine and is, as shown in Figure 2, provided near its ends with openings to receive fastening devices securing the plate to the beam. The body plate is constructed of the proper width so that the insulator of a conventional hanger may be employed in conjunction therewith. As brought out in Figure 3, the insulator, indicated at 14, is formed at its upper end with a stud 15 which extends freely through the body plate into the beam 13, and depending from the lower end of the insulator is a stud 16 upon which is threaded a short stem 17. Pivoted upon the stem are coacting jaws 18 engageable with a trolley wire, as conventionally illustrated at 19, and slideable upon the stem is a wedge member 20 coacting with the jaws. Threaded upon the stem to engage said wedge member is a nut 21 which, as will be seen, may be adjusted for forcing the wedge member downwardly and binding the jaws 18 in engagement with the trolley wire.

In conjunction with the body plate 10, I employ a yoke 22 provided, at one end with arms 23 terminating in ears 24 adapted to freely fit between the ears at either end of the body plate and extending through said ears is a pivot pin 25 swingingly mounting the yoke. At its inner end portion, the yoke is recessed at its lower side to seat the free end of the adjacent bracket 12 of the body plate so that the yoke will normally be sustained in horizontal position by said bracket, and extending freely through the slot 13 of the bracket is a cap bolt 26 threaded through the yoke. Throughout the major portion of its length, the yoke is slotted to freely receive a sleeve 27 which, as shown in Figure 2, is oblong when viewed from the upper end thereof and, as brought out in Figure 1, the sides of the sleeve are gradually widened forwardly and downwardly while the forward end wall of the sleeve is proportionately thickened to carry a forwardly projecting lug 28 mounting a set bolt 29 to coact with

the forward end of the yoke there beneath. Snugly fitting at its upper end in the sleeve is a depending arm 30 of suitable insulating material. This arm may be fixed to the sleeve by rivets or other suitable fastening devices and extending through the sides of the yoke and through the sleeve and arm is a bolt 31 swingingly mounting the arm. Fitting over the lower end of the arm 30 is a pair of clamping jaws 32 recessed, as brought out in Figure 5, to accommodate the arm in mating relation, and extending through the jaws and through the arm is a bolt 33 connecting the jaws thereto. At their lower edges the jaws are curved and are formed with a groove to accommodate a conductor wire 34 while the rear ends of the jaws extend at the rear of the arm and are grooved to receive the adjacent end of the wire therebetween. Extending through the rear extremities of the jaws is a bolt 35 clamping the jaws in engagement with the wire. The conductor wire may thus be easily and quickly connected with the arm 30 by means of said jaws and as shown in Figure 1, the arm is of a length to support the conductor wire directly over the trolley wire 19 in spaced relation thereto.

Attention is now directed to the fact that by adjusting the bolt 29, the sleeve 27 may be rocked upon the yoke 22 for swinging the arm 30 and tightening the conductor wire 34. Accordingly, this conductor wire may be readily drawn taut and any slack occurring therein from time to time easily taken up. The pull of the wire 34 upon the yoke 22 will, of course, tend to swing said yoke upwardly so that by turning the bolt 26 in one direction, the yoke may be permitted to rise for elevating the conductor wire with respect to the trolley wire 19 while by turning said bolt in the opposite direction, the yoke may be rocked downwardly for lowering the conductor wire with respect to the trolley wire. The elevation of the conductor wire above the trolley wire may thus be easily varied. In Figure 5 the conductor wire is shown extending toward the right over the trolley wire. However, should it be desired to mount the conductor wire to extend toward the left, the yoke 23 may be detached from the body plate 10 and shifted to the other end thereof. Thus, the hanger may be utilized at either end of the conductor wire. In my improved signaling system previously referred to, the conductor wire is employed above the trolley wire so that when the trolley wire is lifted by the travel of a trolley along the wire, either the trolley or the trolley wire will contact the conductor wire so that current will be supplied thereto for energizing certain signals.

Having thus described the invention, what is claimed as new is:

1. A hanger of the character described including a double-ended body plate, and a wire supporting device reversible upon the body plate from one end to the other thereof.

2. A hanger of the character described including a body plate, a yoke carried thereby, an arm swingingly mounted upon the yoke, wire engaging means carried by the arm, and means to coact between the arm and yoke for swinging the arm and tensioning the wire.

3. A hanger of the character described including a body plate, a yoke carried thereby, a sleeve pivoted upon the yoke, an arm carried by said sleeve, wire engaging means carried by the arm, and means to coact between the sleeve and yoke for rocking the sleeve and swinging the arm to tension the wire.

4. A hanger of the character described including a body plate, a swingingly mounted arm sustained thereby, mating clamping jaws recessed to fit over the arm, means for clamping said jaws in engagement with a wire, and means for swinging the arm and tensioning the wire.

5. A hanger of the character described including a body plate provided with a bracket, a yoke pivoted to the plate and resting upon said bracket, means coacting between the bracket and yoke securing the yoke stationary, and wire engaging means carried by the yoke.

6. A hanger of the character described including a body plate provided at each end thereof with means to receive a wire supporting device as well as with a fixed projecting bracket, a wire supporting device to cooperate with either of said receiving means selectively resting upon a corresponding one of said brackets, and means for connecting the device with either of said receiving means.

7. A hanger of the character described including a body plate provided at each end thereof with means to pivotally receive a wire supporting device as well as with a fixed projecting bracket, a wire supporting device to cooperate with either of said receiving means selectively, and a single means to selectively cooperate with said receiving means for pivotally connecting said device with either of said receiving means limited against movement in one direction by a corresponding one of said brackets.

8. A hanger of the character described including a body plate provided at the ends thereof with lugs to receive a wire supporting device as well as with projecting brackets, a wire supporting device to cooperate with said lugs selectively whereby said device may be reversed from one end to the plate to the other, and a pivot pin to selectively cooperate with said lugs for

- pivottally mounting said device at either end of the plate limited against movement in one direction by a corresponding one of said brackets.
9. A hanger of the character described including a body plate, a wire supporting device carried thereby and including means for tensioning the wire, and means for adjustably elevating the wire independently of said tensioning means.
10. A hanger of the character described including a body plate, a wire supporting device pivotally connected therewith, means adjustable upon said device for tensioning the wire, and means for adjustably swinging said device and varying the elevation of the wire.
11. A hanger of the character described including a body plate, a wire supporting device pivotally connected therewith and including a pivotally mounted wire carrying arm, means for adjustably swinging said arm and tensioning the wire, and means for adjustably swinging said device and varying the elevation of the wire.
12. In a hanger of the character described, the combination with a body plate, of means associated with the plate for suspending a wire, means carried by the plate for supporting a second wire adjacent said first mentioned wire, and means for tensioning the latter wire independently of the former wire.
13. In a hanger of the character described, the combination with a body plate, of means associated with the plate for suspending a wire, means carried by the
- plate for supoorting a second wire adjacent said first mentioned wire, and means for adjustably elevating the latter wire independently of the former wire.
14. In a hanger of the character described, the combination with a body plate, of means associated with the plate for suspending a wire, means carried by the plate for supporting a second wire adjacent said first mentioned wire, means for tensioning the latter wire independently of the former wire, and means for adjustably elevating the latter wire independently of the former wire.
15. In a hanger of the character described, the combination with a body plate, of means associated with the plate for suspending a wire, means pivotally connected with the plate for supporting a second wire adjacent the former wire, and means for adjustably swinging said supporting means and varying the elevation of the latter wire independently of the former wire.
16. In a hanger of the character described, the combination with a body plate, of means associated with the plate for suspending a wire, means connected with the plate for supporting a second wire adjacent the former wire and including a pivoted wire carrying arm, and means for adjustably swinging said arm and tensioning the latter wire independently of the former wire.

In testimony whereof I affix my signature.

ALBERT J. GURNEY. [L. s.]
